US0D1028611S

(12) **United States Design Patent** (10) Patent No.: **US D1,028,611 S**
(45) Date of Patent: ** May 28, 2024

(54) **PORTABLE BLENDER LID**

(71) Applicant: **BlendJet Inc.**, Benicia, CA (US)

(72) Inventor: **Ryan Michael Pamplin**, San Juan, PR (US)

(73) Assignee: **BlendJet Inc.**, Benicia, CA (US)

(**) Term: **15 Years**

(21) Appl. No.: **29/834,322**

(22) Filed: **Apr. 11, 2022**

(51) LOC (14) Cl. **07-02**

(52) U.S. Cl.

USPC **D7/391; D7/413**

(58) **Field of Classification Search**

USPC D7/213, 300, 305, 310, 312, 314, 317, D7/321, 322, 354, 356, 358, 360, 361, D7/366, 378, 387, 391, 392, 392.1, 396.2, D7/402, 412, 413, 415, 601, 602, 603, D7/605, 607, 608, 612, 615, 619.1, 619.2, D7/622, 629, 703, 709, 630, 510, 511; D9/414, 434, 435, 436, 443, 445, 452, D9/453, 454, 502, 503, 504, 516, 523, D9/528, 529, 530, 531, 535, 549, 569, D9/574, 575, 738, 761, 425; D3/202

(57) **CLAIM**

The ornamental design for a portable blender lid, as shown and described.

DESCRIPTION

FIG. 1 is a front view of a portable blender lid, showing the new design;

FIG. 2 is a side view thereof;

FIG. 3 is a top view thereof; and,

FIG. 4 is a perspective view thereof.

1 Claim, 3 Drawing Sheets
